UNITED STATES PATENT OFFICE.

JOHN J. HERMON, OF OLATHE, KANSAS.

PORTABLE FENCE.

SPECIFICATION forming part of Letters Patent No. 249,763, dated November 22, 1881.

Application filed August 29, 1881. (No model.)

To all whom it may concern:

Be it known that I, JOHN J. HERMON, of Olathe, in the county of Johnson and State of Kansas, have invented certain new and useful 5 Improvements in Portable Fences; and I do hereby declare that the following is a full, clear, and exact description of the invention, which will enable others skilled in the art to which it appertains to make and use the same, reference being had to the accompanying drawings, which form a part of this specification.

My invention is an improvement in portable fences. It is constructed in sections, and can be easily put up and taken down. It is provided with a ground sill and braces, secured by stakes driven in the ground, the whole constituting a fence that is firm, reliable, and durable. The readiness with which it can be manufactured, erected, and taken down makes 15 it especially useful and desirable for farmers. It is particularly adapted to use on pasture, stock, and stubble fields. I accomplish these results by the construction of a fence such as is shown in the accompanying drawings, of 20 which—

Figure 1 is a perspective view of my improved fence. Fig. 2 represents an end view or sectional elevation, showing sill and braces in the manner in which they appear when 25 erected on a hillside or upon uneven ground. Fig. 3 is a side view of one of the stakes used to secure the sill to the ground. Fig. 4 is a side view of the pieces used for bracing the fence at corners.

Similar letters refer to similar parts throughout the several views.

A A' represent two sections of the fence, secured together by sill G, braces F E, and connecting-bolts c and O. The bolt c passes 30 through the posts B B' and concentrated ends of the braces F E. The bolt O passes through the sill G and into the ends of posts B B', respectively. The several sections are thereby held firmly to the sill and braces. The posts 35 B B' are provided with recesses to receive the parallel horizontal boards or panels. The depth of the recess equals the thickness of the panel, so that the one fits flush within the other.

They are secured together by nails or other suitable means.

D D' are vertical cross pieces or cleats, nailed to each of the horizontal panels. They are designed to add strength to the fence.

I I' are side braces, inserted in the ground at their lower ends, and fastened to the top panels by means of hooks b b and staples a a. The hooks b b have shanks which pass through the panels. The braces are placed at convenient angles, so as to prevent the fence from being blown or pushed over.

In Fig. 2 the fence is shown on a side-hill, or upon an uneven piece of ground. The panel is standing in a vertical position, while the sill G conforms to the angle of inclination of the ground. In such cases an additional hole is required in the end of the post B, and also in the brace F or E, to receive bolt c. In addition to the strength and rigor imparted to the fence by means of the sill and braces, the stake H is driven in the ground, and its top or right-angled part overlaps the sill G, thus rendering the structure doubly secure. Two stakes to a 55 sill are designed to be used, one on each side.

In Fig. 4 the brace is shown that is used in turning corners. It represents half of sill G with one of its braces, F. It is to be placed on the outer side of the fence at the point where the turn is made, and it is secured to the end of the fence by means of bolts similar to those used to secure the sill and braces F E. The 60 stake H is used to fasten it firmly to the ground.

Having thus described my invention, I claim as new and desire to secure by Letters Patent—

The combination, in a portable fence, of the sill G and braces E F, secured to post B by 65 means of bolts c O, and the stake H, substantially as set forth, and for the purposes described.

In testimony that I claim the foregoing as my own, I have hereunto affixed my signature 70 in presence of two witnesses.

JOHN J. HERMON.
